F. A. SMITH

LIQUID FUEL SUPPLY DEVICE FOR INTERNAL COMBUSTION ENGINES

Filed April 16, 1924

INVENTOR

Frederick Gorham Smith
By my Attorney
This 31st

UNITED STATES PATENT OFFICE.

FREDERICK ARTHUR SMITH, OF BRASTED, ENGLAND.

LIQUID-FUEL SUPPLY DEVICE FOR INTERNAL-COMBUSTION ENGINES.

Application filed April 16, 1924. Serial No. 707,009.

To all whom it may concern:

Be it known that I, FREDERICK ARTHUR SMITH, a subject of the King of England, residing at Brasted, Kent, England, have invented certain new and useful Improvements in Liquid-Fuel Supply Devices for Internal-Combustion Engines.

This invention is for improvements in or relating to liquid fuel supply devices for internal-combustion engines and has for its main object to provide a simple form of device for supplying a priming charge of liquid fuel to the engine for starting purposes.

Another object of the invention is to provide means whereby a priming charge of liquid fuel alone is followed by a combustible mixture of fuel and air or air alone, independently of or in conjunction with the main fuel supply. The present invention also aims at providing a simple device which is designed as an attachment for use with an ordinary carburettor.

According to a primary feature of the present invention there is provided a device for the purpose above set forth comprising a reservoir-conduit having an air inlet at one end, means at the other end for attachment to an engine induction-pipe to communicate therewith at one or more points therein (on the engine side of the throttle) and means such as a fuel feed-orifice in said reservoir-conduit adapted to be placed in communication with a liquid fuel supply (for example, the float-chamber of the main carburettor) for supplying liquid fuel to said reservoir, with or without means for shutting off at will communication between the reservoir-conduit and the induction pipe.

According to another feature of the invention, a device as described in the preceding paragraph is provided with means for shutting off at will communication between the liquid fuel supply and the reservoir-conduit.

Conveniently, the reservoir-conduit takes the form of a pendent U-tube whereof the end of one limb is open to the air inlet and the other limb is provided with means for connection to the engine induction-pipe and a fuel feed orifice communicates with the tube at a point below the normal level of the supply liquid.

Other features of the invention will be hereinafter described and pointed out in the claims.

In the accompanying drawings:

Figure 1 is a perspective view of one form of apparatus with parts thereof broken away for clearness. In this view the device is shown attached to an engine, portions of the relevant parts thereof being shown.

Figure 2 is an enlarged sectional view on the line 2-2 of Figure 1, showing the annular discharge nozzle.

Figure 3 is a front elevation of a modified form of the device.

Figure 4 is a front elevation of another modified form of the device.

Like reference numerals refer to like parts in the various figures.

The fitting 5 which is common to all the forms of the invention herein shown and described, comprises a tubular part 6 which constitutes a portion of the reservoir-conduit, and which is provided with a fuel inlet orifice 7. The top of this tubular part is bell-mouthed and constitutes the air inlet, being preferably provided with a detachable cup-shaped member 8 having gauze 9 across the mouth. The orifice 7 opens into the filter chamber 10 having suitable gauze strainers therein as indicated, and this chamber is provided with a union 11 for attachment to a liquid fuel supply pipe 12. As shown in Figure 1, the fuel supply is derived from the main carburettor, the pipe 12 being attached to the plug 13 below the jet 14.

Projecting from the part 6 on the side opposite the filter-chamber is an internally screwed boss 15 which accommodates the needle-valve 16 for controlling the flow of fuel through the orifice 7. The head 17 of the needle-valve is milled and is provided with a notch 18 indicated by an arrow. An arm 19 having a split boss 20 which engages the boss 15 aforesaid carries a spring finger 21 for engagement with the milled head 17. The split boss 20 is provided with a clamping screw 22. This mechanism constitutes the needle-valve control and its object is to provide for a "permanent setting" of the device. Thus by loosening the clamp, and with the spring finger engaging the notch, rotating the whole about its axis the position of the valve for normal conditions is ascertained and the clamp is then tightened up. Any temporary adjustment of the valve may afterwards be made by rotating the milled head relatively to the finger which

will always indicate the "permanent setting" position of the valve.

In the construction shown in Figure 1, the remainder of the reservoir-conduit is constituted by the U-tube 23, one limb of which is secured to the tubular part 6 whereas the other limb carries a two-way cock 24 through which communication is made by way of the tube 25 and the annular discharge nozzle (Figure 2) with the engine induction pipe 26. In one position of the cock the tube 25 is in direct communication with the atmosphere by way of the hole 27, and in this position the tube 23 is closed to engine suction. Figure 2 shows a convenient construction for the discharge nozzle which comprises a union 28 screwed into the induction pipe and having a plug 29 with a conical head 30 fixed therein. A number of holes 31 provide passages through the plug to the annular space 32 between the head and the union.

With the arrangement shown in Figure 1, it will be seen that fuel will accumulate in the tube 23 until it reaches the level of the supply, when the engine is not running or when the cock 24 is closed. When the engine is started, the cock 24 being open, a rich priming charge is supplied to the engine, which charge is followed by a mixture of fuel and air after the fuel in the reservoir has been exhausted, because air is drawn from the inlet past the feed-orifice 7 and thus becomes carburetted, the device then functioning as a miniature carburettor.

In the arrangement shown in Figure 3 the cock 24 is located below the fuel inlet and the reservoir is constituted by the cup 8 and the portion of tube above the cock when this latter is closed. In this figure the fuel supply is indicated diagrammatically as coming from a small separate tank 33 which may contain a more volatile fuel than that of the main supply. The supply of fuel to the reservoir can be controlled by the needle valve 16, 17. Obviously, this arrangement may be applied to any of the constructions shown.

Figure 4 shows an arrangement of the device for starting two engines; a particular application being to a large power plant, such as a marine engine, which has a small auxiliary engine for starting it. To the lower end of the part 6 of the fitting 5 two tubes 34 and 35 are attached, the small one 34 being arranged to serve the small starting engine and the large one 35 the main engine. The tube 35 is coiled at 36 so that the capacity of the reservoir formed thereby is increased while at the same time the bore of the conduit remains constant. Above the cock 24 the engine supply pipe 25 branches off to serve the induction pipe at two points; although any number of branches may be employed as desired. The above features

are applicable to any of the constructions according to the invention and are particularly useful in the case of large engines, the latter especially where a long induction pipe is used. The fitting 5 is provided with a pair of lugs 37 to which the reservoir tube or tubes may be secured by solder or the like as shown in Figure 4. In Figure 1 the tube 23 is shown away from the lug for clearness. Again, in Figure 4, the air inlet is shown as provided with a tube 38 through which hot air may be drawn. This arrangement is advisable in any case where the device is intended to be used as a permanent slow running means. When used on a motor car, suitable means may be provided for controlling the cock from the dash.

I claim:

1. A priming device for an internal-combustion engine, comprising in combination a substantially continuous reservoir tube having an air inlet at one end and means at the other end for attachment to the engine induction pipe to communicate therewith, a liquid-fuel inlet to said tube, means for supplying liquid-fuel to said inlet, and a three-way control-cock between said inlet and the induction pipe, which in one position opens a port to admit air to the engine side of the tube and shuts off communication between the engine and the fuel reservoir so that air alone is admitted to the engine, substantially as described.

2. A priming device for an internal-combustion engine, comprising in combination a substantially continuous reservoir tube having an air inlet at one end and means at the other end for attachment to the engine induction pipe to communicate therewith in at least one point, a liquid-fuel inlet to said tube, a filter-chamber communicating with said liquid-fuel inlet, means for supplying liquid-fuel to said filter-chamber, and a control-cock between said inlet and the induction pipe adapted to shut off communication therewith, substantially as described.

3. A priming device for an internal-combustion engine, comprising in combination a substantially continuous reservoir tube having an air inlet at one end and a spray nozzle at the other end adapted to communicate with the engine induction pipe, a liquid-fuel inlet to said tube, a filter-chamber communicating with said liquid-fuel inlet, means for supplying liquid-fuel to said filter-chamber to flood the tube when not under the influence of suction, a regulating valve adapted to control said liquid-fuel inlet, and a three-way control-cock between said inlet and the induction pipe adapted to shut off communication therewith and to open communication between the induction pipe and an air inlet port, substantially as described.

4. A priming device for an internal-com-

- bustion engine, comprising in combination a substantially continuous reservoir tube having a removable cap adapted to form an air inlet at one end and an annular spray nozzle at the other end adapted to communicate with the engine induction pipe, a liquid-fuel inlet to said tube, a filter-chamber communicating with said liquid-fuel inlet, means for supplying liquid-fuel to said filter-chamber to flood the tube when not under the influence of suction, a regulating needle-valve adapted to control said liquid-fuel inlet, and a three-way control-cock between said inlet and the induction pipe adapted to shut off communication therewith and to open communication between the engine and an air inlet port, substantially as described.
5. A priming device for an internal-combustion engine, comprising in combination a pendent **U** tube having one limb open to atmosphere to constitute an air inlet, means at the end of the other limb for attachment to the engine induction pipe to communicate therewith, a liquid-fuel inlet communicating with one of said limbs, and means for supplying liquid-fuel thereto from the float chamber of the engine carburetor, substantially as described.
10. A priming device for an internal-combustion engine, comprising in combination a pendent **U** tube having one limb open to atmosphere to constitute an air inlet, means at the end of the other limb for attachment to the engine induction pipe to communicate therewith, a liquid-fuel inlet communicating with one of said limbs, and a three-way control-cock between said fuel inlet and the induction pipe, which in one position opens a port to admit air to the engine side of the tube and shuts off communication between the engine and the fuel reservoir so that air alone is admitted to the engine, substantially as described.
15. A priming device for an internal-combustion engine, comprising in combination a pendent **U** tube having one limb open to atmosphere to constitute an air inlet and an annular spray nozzle at the end of the other limb adapted to communicate with the engine induction pipe, a liquid-fuel inlet communicating with one of said limbs, means for supplying liquid-fuel to said inlet to flood the tube when not under the influence of suction, and a three-way control-cock between said fuel inlet and the induction pipe adapted to shut off communication therewith and to open communication between the engine and an air inlet port, substantially as described.
20. A priming device for an internal-combustion engine, comprising in combination a pendent **U** tube having one limb provided with a removable cap to constitute an air inlet, a spray nozzle at the end of the other limb for attachment to the engine induction pipe to communicate therewith, a liquid-fuel inlet communicating with one of said limbs, a regulating valve adapted to control said liquid-fuel inlet, and a control-cock between said fuel inlet and the induction pipe adapted to shut off communication therewith, substantially as described.
25. A priming device for an internal-combustion engine, comprising in combination a pendent **U** tube having a perforated cap adapted to form an air inlet at one end of one limb, a spray nozzle at the end of the other limb adapted to communicate with the engine induction pipe, a liquid-fuel inlet in one of said limbs, a filter-chamber communicating with said fuel inlet, means for supplying liquid-fuel to said filter-chamber from the float chamber of the engine carburetor, a regulating valve for said fuel inlet, and a control-cock between the fuel inlet and the induction pipe adapted to shut off communication therewith, substantially as described.
30. A priming device for an internal-combustion engine, comprising in combination a substantially continuous reservoir tube having an air inlet at one end and means on the other end for attachment to the engine induction pipe to communicate therewith in one point, a liquid-fuel inlet to said tube, a regulating valve adapted to control said fuel inlet and means for supplying liquid-fuel to said inlet, control means operatively connected to said regulating valve in such a manner as to permit relative movement between said valve and said control means and provided with means to permit, at will, bodily movement of the control means with said valve, and a control-cock between said fuel inlet and the induction pipe adapted to shut off communication therewith, substantially as described.
35. A priming device for an internal-combustion engine, comprising in combination a reservoir tube having one end open to atmosphere to constitute an air inlet and means at the other end for attachment to

the engine induction pipe to communicate therewith, a liquid-fuel inlet communicating with said tube, a boss on said tube, a needle valve having a screw-threaded engagement in said boss and adapted to control said liquid fuel inlet, a milled head for turning said valve, a sleeve rotatably mounted on said boss, means to clamp said sleeve to said boss, an arm secured to said sleeve and adapted to be rotated therewith and a catch on said arm adapted to engage said milled head, substantially as described.

13. A priming device for an internal-combustion engine, comprising in combination 15 a pendent U tube having a removable perforated cap adapted to form an air inlet on one limb, an annular spray nozzle at the end of the other limb adapted to communicate with the engine induction pipe, a 20 liquid-fuel inlet communicating with one of said limbs, a filter-chamber communicating

with said liquid-fuel inlet and having means for supplying liquid-fuel thereto from the carburetor of the engine, a boss on said tube, a needle valve having a screw-threaded engagement in said boss and adapted to control said liquid-fuel inlet, a milled head for turning said valve and having an indicator thereon, a sleeve rotatably mounted on said boss, means to clamp said sleeve to said boss, an arm secured to said sleeve and adapted to be rotated therewith, a catch on said arm adapted to engage said milled head, and a three-way control-cock adapted to shut off communication between the fuel inlet and the induction pipe and to open up communication between the induction pipe and an air inlet port in the casing of said cock, substantially as described.

In testimony whereof I affix my signature.

FREDERICK ARTHUR SMITH.
